UNITED STATES PATENT OFFICE.

JACOB H. MORROW, OF EUREKA, ILLINOIS, ASSIGNOR TO HART GRAIN WEIGHER COMPANY, OF PEORIA, ILLINOIS, A CORPORATION OF ILLINOIS.

ELEVATOR.

1,160,523.

Specification of Letters Patent. Patented Nov. 16, 1915.

Application filed March 17, 1913. Serial No. 754,727.

To all whom it may concern:

Be it known that I, JACOB H. MORROW, citizen of the United States, residing at Eureka, in the county of Woodford and 5 State of Illinois, have invented certain new and useful Improvements in Elevators, of which the following is a specification.

My invention has reference more particularly to elevators wherein there is provided 10 an adjustable receiving end section for maintaining the conveying device of the elevator at a tension to operate properly.

The object of my invention is to provide 15 the elevator with an adjustable boot section so formed with reference to the lower end of the elevator as to provide an uninterrupted continuous elevator passage way in its different positions of adjustment.

A further object is the maintaining of the 20 elevator directing mechanism in the adjustable boot for the purpose of regulating the tension of the conveying means by adjustment of the boot and also so as to provide an unchanged relation between the conveying 25 means and the bottom of the boot in any position of adjustment.

A further object is the provision of means 30 for delivering material into the boot which adjusts itself automatically to accord with the different positions of the boot.

A further object is the supporting of the 35 boot by means of the conveying mechanism so as to automatically regulate the tension of the conveying mechanism by means of the weight of the boot and the material contained therein.

The invention also embraces other features which will appear from the following 40 specification and which are particularly pointed out in the claims.

Referring to the drawings—Figure 1 is a side elevation of a portion of the elevator showing parts broken away to accommodate a view of interior arrangement of parts; 45 Fig. 2 is a section on line $a-a$ of Fig. 1; Fig. 3 is a partial section on line $a-a$ of Fig. 1, showing a slightly different position of parts from that disclosed in Fig. 2, and in addition showing a means of fixing relatively movable parts; Fig. 4 is a sectional view on the line $b-b$ of Fig. 3 with the addition thereto of a diagrammatic illustration of a cross conveyer or drag.

50 Mechanical devices for handling grain upon the farm, and particularly ear corn,

have come rapidly into use within the last few years, in place of manual labor previously exercised in the use of scoops and the like. The portable dump and elevator has been the principal agency in this regard, 60 wherein a wagon raising means called a dump has been associated with an elevator and built so light that the complete structure was transportable from place to place. In its use, such dumps and elevators have 65 been moved lengthwise of corn cribs or warehouses, and thus have proven adaptable for convenient filling and grain handling.

With the increase of wealth of the farmer, and in view of the demonstrated efficiency 70 and utility of machine handling of grain, large permanent warehouses have been built to take the place of the old time corn cribs, which latter were of a more temporary character and of a cheap construction.

An elevator permanently built into a warehouse making it a part of such warehouse must be positioned substantially vertical as distinguished from the inclined position of an elevator in portable structures, therefore 80 the conveyer chain must bear the whole load and is under heavy strain and liable to stretch. It is one of the purposes of my invention to take care of this change in length of chain.

In handling ear corn with the vertical elevator, great difficulty has been experienced from clogging in the boot, caused by buckling of the conveyer chains. This has been due largely to a difficulty of maintaining a 90 permanency of relative position between the interior surface of the boot and the carrier buckets; to the looseness or lack of permanency as to position of the buckets themselves, due to slack chain, and to clearance 95 between the elevating devices and the walls of the boot which permits husks, refuse, and even ears of corn to drop downwardly and become wedged within the boot so as to obstruct operation of the conveying means 100 within the boot.

Referring to the drawings, 2 refers generally to a casing which may be of general rectangular shape provided with substantially close side walls and with partially or 105 wholly closed front and rear walls.

3 refers generally to castings, being located respectively one upon each side of the elevator, a portion of such sides being connected with framework of any suitable 110

character to accommodate the support of said castings and to extend the elevator to any desired height.

Referring to castings 3, 4 are channels 5 formed in the inner face of the castings and are adapted to receive similar channel way portions in castings hereinafter to be described to facilitate relative adjustment of said castings in controlled lines, and also 10 serving as a guideway or channel, through which the conveyer chains may travel. The castings 3 are adapted to be connected by means of a rod 6 provided at each end with a pair of adjustment nuts 7 to facilitate the 15 proper spacing apart of said castings and to accommodate adjustment thereof to render their placement relative to the conveyer mechanism in the proper relation to prevent binding, or too much lost space.

20 8 are castings formed to sit within the offset 5 of castings 3, said castings being provided with channels 9 previously indicated, adapted to match with channels 4 of castings 3.

25 10 are studs extending laterally from castings 8 adapted to project through elongated openings 11 in castings 3. This stud is provided with a central bore, within which is adapted to be carried the shaft 12, which 30 shaft is adapted to extend across and through the lower portion of the elevator coil, denominated a boot, and to carry the sprocket wheels as 13 (shown in dotted lines in Fig. 1 and also shown in Fig. 4) and over 35 which sprocket chains as 14 are adapted to be carried, the latter carrying buckets 15, as shown in Fig. 4. A front, bottom and rear housing wall 16 is provided, as shown in Figs. 2 and 4, adapted to form a closure between the castings 3 and said wall may be 40 extended and inclined as at 17 to meet a pivoted apron as 18 to form a chute leading to the boot of the elevator.

19 refers generally and in a diagrammatic 45 manner to a drag or cross conveyer that is adapted to be built underneath the floor of the driveway, and purposed to receive, through an openable way, the discharge of grain from the wagon and to deliver the same to the elevator.

50 20 is a partition adapted to be fixed to lugs as 21 on castings 8 (and by other means, if desired) and is curved about shaft 12 to form a closure or shield thereabout. The 55 partition 20 extending upwardly lies within guideway 22, the latter being formed by proper spacing of the frame parts of the elevator body. The partition 20 is adapted to have a bearing relation with partition 23, 60 which latter extends upwardly from its connection with casting 3.

The space between the partition and the front and rear walls respectively of the boot and the elevator form the passageway for 65 the conveyer, and its buckets. The chains

being supported in the head of the elevator and driven in the usual way. The chains 14, when they leave the channels 9 and castings 8, may be positioned relative to the side walls to be carried in channels formed in the 70 elevator framing by properly spacing such framing substantially in the manner shown in the drawings. Two lugs as 21 are provided on casting 8, as shown in Fig. 4, merely to provide interchangeability of said 75 castings from side to side or to adapt them to use on either side of the elevator structure.

In the normal working of my device, the boot portion of the elevator, comprising castings 8 and their associated parts, including closure wall 16, is suspended from sprocket chains 14, thus fixing the position of the buckets with the closure wall 16, permanently so that there can be no variation of their relation under any normal condition. The carrying of the elevator boot by the chains 14 serves to render them tight at all times. The facility for vertical adjustment between the boot and castings 3 forming part of the elevator body, is permitted 90 through the clearance provided in and by the elongated openings 11 in said castings 3, and I have shown by the channel formations within castings 3 and 8, guiding efficiency therebetween, and have likewise shown the 95 facility for relative adjustment between partition 20 of the boot and partition 23 thereabove and in the body of the elevator. In operation, there is an automatic co-adjustment between the parts that takes care of 100 all conditions that grow out of a lengthening or shortening of the conveying element.

In Figs. 1 and 3 I have shown a means for fixing the boot with relation to the elevator body or castings 8 thereof. This means comprises threaded stems as 24, which may be fixed in connection with studs 10. 25 are perforated lugs on castings 3 through which threaded stems 24 are passed. 26 are spacing nuts adapted to accomplish adjustment between the parts named and also serve to fix the parts in a definite position.

I have shown herein one means of embodiment of my invention and in a general way, the means disclosed has been demonstrated 115 efficient for the purpose, and is at present my preferred form. However, I do not desire to be limited to the form disclosed, but wish the invention to apply to all forms that lie within the scope of the appended claims. 120

What I claim is:

1. In a device of the class described, the combination of an elevator housing, chain conveying mechanism operable in the latter, and a boot member supported by the chain 125 conveying mechanism, having in seats in the sides thereof affording space for sprocket wheels, and provided with channels for housing and guiding the chain conveying mechanism whereby the elevator housing 130

and boot are adjustably related to the movable conveyer and sprocket wheel members are housed against entanglement with the grain being elevated.

5 2. In a device of the class described the combination of an elevator, an adjustable boot for the elevator, and means for directing material into the boot, said means being arranged to automatically change its position to accord with the adjustment of the boot.

10 3. In a device of the class described, in combination, an elevator framework, a boot section reciprocally carried therein, conveyer directing mechanism supported in the boot and movable therewith, conveying mechanism supported to be driven within the elevator body connected with and supporting the boot in a suspended relation, and a fixed partition in the elevator housing and a similar partition in the boot movable relatively in substantial contact as the boot may be raised or lowered.

15 4. In a device of the class described, an elevator housing, cast sections forming the sides of the lower portion thereof provided with seats and channel ways and elongated longitudinally disposed slots, a boot portion comprising side walls channeled and seated to conform with the channels and seats of the said castings of the elevator and provided with laterally extending studs, a closure for the front, rear and bottom portion of the boot connected and secured to said side walls, a conveyer directing mechanism connected with and movable with the said boot, conveyer mechanism suitably supported in connection with the elevator body and supporting the boot section in suspension.

20 5. In a device of the class described, the combination of an elevator stand provided with an inlet and comprising suitable housing members, elevating mechanism therein comprising a movable element suitably supported to be driven, a boot member within the elevator stand adjustable longitudinally thereof and supported in a suspended relation within the stand by the elevator mechanism, a conveyer member communicating for discharge with the boot member within the elevator stand and a chute or deflector member connecting the elevator and said boot member, and suitably supported to be moved by and with the movement of the boot member.

25 6. In a device of the class described, the combination of an elevator housing, chain elevating mechanism suitably supported and driven therein, a boot member supported within the housing and adjustable under expansion and contraction of the chains of the elevating mechanism, a fixed partition in the elevator housing, an extension of said partition connected with the boot member and overlying said fixed partition and ad-

justable relatively thereto when the boot member is raised or lowered.

30 7. In a device of the class described, in combination, an elevator housing, elevating mechanism therein, suitably supported to be operated, a fixed partition in said housing forming ways on either side thereof for the travel of the elevating mechanism, a boot member adjustable lengthwise of said housing, a shaft journaled within and extending transversely of said boot member, members for engagement with the elevating mechanism for support of said boot member, a housing for said shaft and an extension of said housing to form a partition in the boot member in a plane adjacent the fixed partition in the elevator housing, a portion thereof overlying said fixed partition.

35 8. In a device of the class described, in combination, an elevator housing including cast members forming the side walls of its lower portion provided with vertically disposed channel ways, elevating mechanism within the housing comprising chain members, driving members therefor and driven members, a boot member vertically adjustable in said housing and adapted to be supported by the elevating mechanism, including in its structure side members formed with in seats for the seating of the driven members of the elevating mechanism and with guide channel offsets therein for the sprocket chains of the elevating mechanism, said offsets registering with the channel-ways in the side members of the elevator housing, a partition within the elevator housing and a similar partition in the boot member, said partitions overlapping each other to render them adjustable relatively and together forming a continuous parti-

40 9. In a device of the class described, in combination, an elevator housing including cast members forming the side walls of its lower portion, provided with vertically disposed channel-ways, elevating mechanism within the housing comprising chain members, driving members therefor and driven members, a shaft supported in the driven members, a boot member vertically adjustable in said housing and adapted to be supported by the elevating mechanism, including in its structure side members formed with in seats for the seating of the driven members of the elevating mechanism and with guide channel offsets therein for the sprocket chains of the elevating mechanism, said offsets registering with the channel-ways in the side members of the elevator housing, a partition within the elevator housing and a similar partition in the boot member, said partitions overlapping each other to render them adjustable relatively and together forming a continuous parti-

10. In a device of the class described, in combination, an elevator housing comprising upper and lower sections, the side members of the upper section being spaced apart 5 relatively to form guideways, and the side walls of the lower section being provided with guideway in seats registering with the guideways in the upper section and also with longitudinally slotted ways, elevating mechanism 10 suitably supported within the housing comprising connected members adapted to be carried within the guideways of the side wall members of the upper and lower sections, means for operating the elevating 15 mechanism, a boot member supported by the elevating mechanism and vertically adjustable in the elevator housing, said boot member being provided with laterally extending lug members engaging the ways in the bottom side members, and a partition in the elevator housing comprising members fixed 20 relatively in the upper section of the elevator housing and in the boot member, side members overlying each other to effect a closure and to permit relative movement 25 thereof.

11. In a device of the class described, in combination, an elevator housing comprising upper and lower sections, the side members of the upper section being spaced apart 30 relatively to form guideways and the side walls of the lower section being provided with guideway in seats registering with the

guideways in the upper section, and also with longitudinally slotted ways, an inlet 35 into the elevator housing, elevating mechanism suitably supported within the housing, comprising connected members adapted to be carried within the guideways of the side wall members of the upper and lower 40 sections, means for operating the elevating mechanism, a boot member supported by the elevating mechanism and vertically adjustable 45 in the elevator housing, said boot member being provided with laterally extending lug members engaging the ways in the bottom side members, and a partition in the elevator housing comprising members fixed relatively in the upper section of the elevator housing and in the boot member, side 50 members overlying each other to effect a closure and to permit relative movement thereof, a conveyer mechanism adapted to communicate through the inlet in the elevator housing, with the boot member, and a chute member serving to establish such communication and supported in a manner to permit it to be moved with the movement of the boot member as the latter may be raised 55 or lowered within the elevator housing.

In testimony whereof I have affixed my signature in presence of two witnesses.

JACOB H. MORROW.
